UNITED STATES PATENT OFFICE.

STEPHEN KRONBURGER, OF JERSEY CITY, NEW JERSEY, ASSIGNOR TO COHAN-EPNER CO., OF NEW YORK, N. Y.

DESIGN FOR AN ASH TRAY.

Application filed May 5, 1921. Serial No. 467,227. Term of patent 7 years.

To all whom it may concern:

Be it known that I, STEPHEN KRONBURGER, a citizen of the United States, residing at 626 Bloomfield St., Jersey City, in the county of Hudson and State of New Jersey, have invented a new and original Design for Ash Trays, of which the following is a specification, reference being had to the accompanying drawing, forming part thereof.

The figure is a perspective view, somewhat enlarged, of my design, the view being in a direction inclined to the base of the ash tray and the figure of the elk rests on a horizontal platform.

I claim:

The ornamental design for an ash tray as shown.

STEPHEN KRONBURGER.
